US0D1095750S

(12) **United States Design Patent** (10) Patent No.: **US D1,095,750 S**
(45) Date of Patent: ** Sep. 30, 2025

(54) **WATER PURIFIER**

(71) Applicant: **Zhisheng Li**, Shenzhen (CN)

(72) Inventor: **Zhisheng Li**, Shenzhen (CN)

(**) Term: **15 Years**

(21) Appl. No.: **29/948,797**

(22) Filed: **Jun. 24, 2024**

(51) LOC (15) Cl. **23-01**

(52) U.S. Cl.

USPC **D23/207**

CLAIM

The ornamental design for a water purifier, as shown and described.

DESCRIPTION

FIG. 1 is a front, left and top perspective view of a water purifier, showing my new design;

FIG. 2 is a rear, right and bottom perspective view thereof;

FIG. 3 is a perspective view, shown in a used condition;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines shown in the drawings illustrate portions of the water purifier that form no part of the claimed design.

1 Claim, 9 Drawing Sheets
